CLAIM

The ornamental design for a shoe, as shown and described.

DESCRIPTION

FIG. 1 is a front lateral perspective view of an embodiment of a shoe.

FIG. 2 is a lateral side view of the shoe of FIG. 1.

FIG. 3 is a medial side view of the shoe of FIG. 1.

FIG. 4 is a front view of the shoe of FIG. 1.

FIG. 5 is a rear view of the shoe of FIG. 1.

FIG. 6 is a bottom view of the shoe of FIG. 1; and,

FIG. 7 is an enlarged partial view of a lateral side of a midsole of the shoe of the encircled area 7 seen in FIG. 2. The dash-dot broken line portions are included to show the boundaries between the claimed and unclaimed portions in FIGS. 1 through 5, as well as defining the area of enlargement in FIGS. 2 and 7. In all instances of their use, the dash-dot lines only and form no part of the claimed design. The stippled surface shading in FIG. 7 is included to show three-dimensional contours only and is omitted from FIGS. 1-6 for ease of illustration.

The remainder of the shoe shown in broken lines in FIGS. 1-6 shows unclaimed subject matter only and forms no part of the claimed design.
